COMBINED COOKING UNIT AND SERVING BAR

Louis J. Jenn and Joseph M. Boarman, Indianapolis, Ind.,
assignors to Jenn-Air Products Company, Inc., Indianapolis, Ind., a corporation of Indiana

Filed Dec. 14, 1962, Ser. No. 72,856

Term of patent 14 years

(Cl. D81—4)

Fig. 2.

Fig. 1.

Fig. 4.

Fig. 3.

Fig. 5.

Fig. 6.

FIG. 1 is a perspective view of a combined cooking unit and serving bar embodying our new design, taken generally from one end thereof and showing the range cover in closed position.

FIGURE 2 is a perspective view as seen from the front and one end thereof with the range cover in open position.

FIGURE 3 is a rear perspective view thereof with the range cover in closed position.

FIGURE 4 is a front elevation thereof.

FIG. 5 is a fragmentary top plan view showing the range cover in open position.

FIG. 6 is a fragmentary top plan view showing the range unit cover in closed position.

The dominant features of our design reside in the portions shown in full lines.

The undisclosed end is plane and unornamented.

We claim:

The ornamental design for a combined cooking unit and serving bar, as shown and described.
